UNITED STATES PATENT OFFICE.

ORVILLE L. ELTINGE, OF CHICAGO, ILLINOIS.

TUNNEL LINING.

Application filed May 27, 1927. Serial No. 194,570.

This invention relates in general to the process of lining of tunnels which are cut in earth of various degrees of softness and is well adapted to be used in the construction 5 of tunnels of any magnitude.

Whether a tunnel is being driven in soft earth or in a rocky formation, some means of temporary support of the roof and sides of the drift is required as the work progresses 10 to prevent the squeezing or caving in of the soft earth or the accidental dislodgement of fragments in a rocky formation. The hitherto employed temporary shoring has not only been expensive to install but usually consti-

15 tutes a great interference with further tunneling operations and is no small impediment to the later task of placing a permanent masonry lining in the tunnel. Both of the disadvantages of temporary shoring are obviated 20 by my method of tunnel construction and new advantages not heretofore known are made possible. The construction which serves the purpose of a temporary shoring as disclosed in this application is also allowed to 25 remain in position and becomes a valuable part of the permanent lining of the tunnel.

One of the objects of this invention is to provide a lining for a tunnel, a portion of which serves as a temporary shoring and so 30 serves without hindrance to further tunnel operations.

Another object of this invention is to provide a tunnel lining which serves as a temporary system of shoring and which is later 35 incorporated into the permanent shell conveniently and at a remarkably low cost.

Another object of this invention is to provide a method of tunnel lining in which temporary shoring is built up in short sections 40 as the tunneling progresses and which leaves a clear central passage for further tunneling operations.

Another object of this invention is to provide a method of tunnel lining in which temporary shoring is erected in short sections 45 and does not interfere with further tunneling operations and which may later be incorporated into the permanent shell of the tunnel.

Another object of this invention is to provide a system of shoring for a tunnel during construction which leaves a free working 50 passage and which is incorporated into the permanent lining of the tunnel.

Another object of this invention is to provide a system of shoring a tunnel during con-

struction which leaves a free working passage and which is incorporated into the permanent lining of the tunnel serving during such incorporation to save the later added 60 material from strain until such material has become permanently set in place.

Another object of this invention is to provide a reinforcement for tunnel linings which may be brought into the tunnel in small 65 pieces and erected in small units which are eventually formed into a rigid tunnel reinforcement which serves both as a temporary shoring and which becomes part of the permanent lining of the tunnel.

Another object of this invention is to provide a method of tunnel lining which is capable of being adapted to any type of soil condition and lends itself to rigid and economical tunnel construction.

Other objects, advantages and capabilities are inherent to this invention and will later become apparent.

Referring now to the drawings in which an embodiment of the invention is illustrated,

Fig. 1 is a cross sectional view of a tunnel equipped with the temporary shoring which sustains the lagging and walls until it is desired to construct the permanent lining.

Fig. 2 is another view of the same construction showing wooden forms placed inside of the rigid frame to be utilized when pouring the permanent concrete shell of the tunnel, thus incorporating the temporary shoring into the tunnel lining as permanent 90 reinforcement.

Fig. 3 is a longitudinal sectional view of a tunnel showing a plurality of braces and in permanent position and showing temporary wooden forms for the forming of the concrete shell.

Fig. 4 illustrates the staggered arrangement of the lagging which may be utilized whenever it is possible to insert lagging strips of sufficient length to accomplish this.

Referring now in detail to the drawings, the reinforcement is shown as applied to a tunnel of cylindrical shape, though, of course, this reinforcement could be used either in whole or in part equally well for 105 tunnels of other shapes. Lagging consisting of planks 11 of suitable dimensions are placed upon the bottom of the tunnel and a bottom section 12 of the frame is placed above the lagging and separated therefrom by means of wedges 13. The wedges will be 110 so arranged as to dispose this arcuate frame

section on the circumference of a circle whose center is the ultimately desired center line of the tunnel. Thereafter the other two sections 14 and 15 of the frame are connected by means of the pins 16 to each other and to the bottom section 12. When so connected, these three sections form a rigid frame which can not be distorted in any way. The shape of the frame sections and their size 10 make it possible for them to be conveniently carried into the tunnel and therein erected.

Lagging is then placed around the remaining portions of the wall of the tunnel and is separated from the frame by means of the 15 wedges 13. The wedges may be made of wood or any other suitable material and will drive the lagging firmly against the tunnel walls and also cause all of the lagging to be firmly supported by the frame.

20 It is clear then that when the frame and lagging are so arranged, the walls of the tunnel, whether they be soft or reasonably hard are equally well supported and the additional tunneling operations may be continued. The shape of this reinforcement and the free central passage which it affords make it ideal for temporary shoring. The length of the planks used for lagging may vary without altering the usefulness of the 25 invention and the frames may be placed as near to one another in the length of the tunnel as may seem desirable, or the soil conditions require.

Not only is this reinforcement ideal for 30 temporary shoring, but it is adapted to become part of the permanent reinforcement of the tunnel lining. This is accomplished by erecting a temporary form for the retention of concrete, which form will be made up of the sections 17. The sections 17 are fastened together into a rigid frame by means 35 of the cleats 18. Concrete may then be introduced between the perimetral wall 19 of this concrete form and will fill all of the space 40 between that wall, surrounding the frame and extending back to the lagging where it likewise fills in between the wedges and any void spaces between the lagging strips. The frame may be provided with a plurality of 45 holes 21, if desired, to aid the concrete in gripping it. The frame may have any one of many shapes and may be built up of a number of smaller pieces of metal fastened together to form arches or trusses and may be 50 made of exposed metal or may be in part covered with concrete or some other substance 55 set upon a metal frame.

It will be noted that when the concrete form consisting of the sections 17 is removed, 60 the frame is entirely inclosed and the entire temporary shoring has become part of the permanent shell. It is apparent also that the newly poured concrete is not burdened with the pressure from the tunnel walls inasmuch as the walls are still being supported 65

by the lagging, wedges and frame. When the concrete is fully set, it lends additional strength to the frame which is supporting the lagging and serves to oppose some of the thrust of the lagging directly itself. It also 70 locks the wedges in position and prevents any shifting of the lagging inwardly from the position in which it was originally placed. Although a few cleats 22 are shown as separating the forms 17 from the frame work, 75 this was done for purposes of illustration only and need not be resorted to in the actual use of the invention as it is not desirable to allow such cleats to become imbedded in the inner face of the tunnel wall. 80

While concrete is referred to above as the material used in the permanent shell, it is evident that brick, tile or other material may also be used and set firmly around the frame members to reinforce them and be reinforced 85 by them.

While the frame is shown and described as being composed of three parts, it should be understood that a frame made up of two parts may be used equally well and that under some conditions a frame of four or more parts may be used.

It should be understood that the embodiment of the invention disclosed has been selected for the purpose of illustrating the invention and that various modifications and changes may be made without departing from the spirit and scope of the invention.

Having shown and described this invention, 100

I claim:

1. A tunnel lining comprising lagging disposed against the earth walls of the tunnel, a rigid frame within said lagging, means supported by the frame for spacing the lagging apart from the outside of the frame and a masonry shell extending radially within and outside of said frame and reinforced thereby.

2. A method of lining a tunnel comprising disposing a rigid frame within the walls of a tunnel and spaced apart therefrom, placing lagging between the frame and the walls of the tunnel, forcing the lagging against the walls with wedges inserted between it and the frame whereby to support the walls on said frame, and thereafter placing around the frame and wedges a material to form a permanent inner tunnel surface and which is reinforced by said frame.

3. A method of lining a tunnel comprising installing lagging against the walls of a tunnel and supporting the lagging on a rigid frame disposed radially within the lagging, said frame having no portion extending into the ultimately useful area of the tunnel, and bracing the lagging firmly against the walls of the tunnel and apart from the frame whereby the frame and lagging becomes the support for the tunnel walls.

4. A method of lining a tunnel comprising

- installing a rigid frame in a newly formed tunnel section and placing lagging against the earth walls of the tunnel and outside of said frame, spacing the frame generally 5 apart from and within said lagging and supporting the lagging and earth walls on said frame, the frame having no portions extending into the working area and ultimate useful area of the tunnel.
10. 5. A method of lining a tunnel comprising disposing a rigid frame in the tunnel, placing lagging outside of said frame, and separating the lagging from the frame with wedges whereby the earth walls of the tunnel are firmly 15 retained by the lagging which in turn is rigidly supported on the frame, said frame having no portions extending into the ultimately useful area of the tunnel.
6. A method of lining a tunnel comprising placing lagging against the earth walls of the tunnel, supporting the lagging against compression on a rigid frame disposed inside of the lagging and spaced apart therefrom, the frame being of generally annular shape and 25 having no portion extending into the ultimately useful area of the tunnel, and thereafter inclosing said frame with a material to form a permanent inner wall surface of the tunnel.
30. 7. A method of reinforcing a tunnel lining comprising lining the earth walls of the tunnel with lagging, supporting the lagging on a rigid frame and spaced apart therefrom, the frame and lagging adequately supporting said walls at all points and leaving a clear 35 central passage larger than the ultimate internal dimensions of the tunnel for the further work of tunneling, and thereafter inclosing the inner and side surfaces of the frame with a material to form a permanent inner tunnel wall.
40. 8. A method of lining a tunnel comprising setting a rigid frame in position in a tunnel, placing lagging outside of said frame, spacing the lagging apart from the frame by 45 means of wedges bearing on the frame, placing an inner form within the frame and spaced apart therefrom, and pouring concrete into the space between said form and lagging to form a permanent shell for the tunnel with the frame within the concrete as reinforcement therefor.
9. A method of lining a tunnel comprising placing lagging against the earth walls of the tunnel, supporting the lagging against compression on a rigid frame disposed inside of the lagging and spaced apart therefrom, and thereafter surrounding the peripheral, inner and side surfaces of said frame with a material which forms a permanent inner wall surface of the tunnel and which is reinforced by the frame.
10. A method of lining a tunnel comprising disposing a rigid frame within the walls of a tunnel, inserting lagging between the outer surface of the frame and the wall of the tunnel, moving the lagging radially outwardly by driving wedges between it and the frame thereby supporting the lagging on the frame and spaced apart therefrom, and thereafter surrounding the peripheral, the side and the inner surfaces of the frame with a material to form a permanent inner tunnel wall which is reinforced by said frame.
11. A tunnel lining comprising a rigid frame, lagging disposed radially outside said frame, separating members disposed between the lagging and the periphery of the frame for holding the lagging spaced apart from the frame, the frame separators and lagging being adapted to serve as a rigid support for the earth walls of the tunnel prior to the addition of a permanent lining, and a permanent lining enclosing the frame surrounding its peripheral, side and inner surfaces and adapted to be reinforced by the frame.

In witness of the foregoing I affix my signature.

ORVILLE L. ELTINGE.
